BLIND OR SHUTTER

Edward B. Nottingham, Villa Park, Ill., assignor
to H. B. Dodge and Company, Chicago, Ill., a
corporation of Illinois

Application February 3, 1934, Serial No. 709,579

21 Claims. (Cl. 156—16)

This invention relates to blinds or shutters, and more particularly to a rolling shutter having individual slats mounted upon a flexible cable or band.

5 This application is a continuation in part of application Serial No. 672,036, filed May 20, 1933, as to all matter common to both of said applications.

The primary object of the present invention is 10 to provide a new and novel flexible rolling shutter or curtain having spaced apart slats or slats strung upon a flexible support such as a cable or band, the slats being spaced apart by suitable spacer members to permit air to pass between 15 the slats, but preventing vision through said spaces, the spacer members being constructed and arranged to permit flexibility of the curtain, but preventing the spacer members from being compressed, and thereby prevent any one from 20 looking between the spaced slats.

Another object of the invention is to provide an improved flexible rolling curtain made up of a plurality of spaced slats, the slats being constructed so as to have a receiving groove and a 25 projection, the projection adapted to extend a predetermined distance into the groove of an adjacent slat so as to permit air to pass through the slats, but prevent sight through the spaces between the slats.

30 A further object of the invention is to provide a rolling curtain for use in Pullman cars for assembling berths, the curtain comprising a plurality of superimposed slats, the line of vision between the slats being obstructed by depending portions of adjacent slats.

A still further object of the invention is to provide a flexible coiled curtain made up of a plurality of spaced slats, the slats being formed of metal arranged about filler members of substantially the same form and configuration as the slats, there being flexible incompressible members arranged between the slats to hold them in proper spaced relationship.

Further objects of the invention are the provision of a roller curtain for use in connection with Pullman car sleeping berths.

A still further object of the invention is the provision of a Pullman car sleeping berth rolling curtain which is adapted to smoothly and noiselessly operate in vertical grooves; which is provided with means for preventing the individual slats of the curtain from rattling in the grooves; which is provided with protuberances struck from the metal to prevent rattling of the slats in the grooves, and at the same time permitting

easy free operation of the curtain; which is provided with slotted or slit flexible ends to permit a certain amount of friction of the slats in the grooves, and at the same time prevent rattling thereof; which is provided with spacer members 5 formed of compressed coiled springs to permit sufficient flexibility of the curtain to allow it to properly shift from one position to another, but which prevents the slats from being manually spread apart so that it is possible to see between 10 the slats; which is provided with means at the under surfaces of the slats to prevent light from reflecting through the curtain; which is durable in construction, easy and positive in operation, and which can be readily and economically man- 15 ufactured.

Numerous other objects and advantages will be apparent throughout the progress of the following specification:

The accompanying drawings illustrate a 20 selected embodiment of the invention, and the views therein are as follows:

Fig. 1 is a detail longitudinal sectional view taken through a sleeping car and having the invention applied to an upper berth of the car. 25

Fig. 2 is a detail elevation partly in section showing the rolling curtain arranged in closed position.

Fig. 3 is a detail plan section on the line 3—3 of Fig. 2. 30

Fig. 4 is a detail sectional view on the line 4—4 of Fig. 1.

Fig. 6 is a detail vertical section on the line 6—6 of Fig. 5.

Fig. 7 is a detail vertical sectional view through a part of the curtain.

Fig. 8 is a detail sectional view on the line 8—8 of Fig. 6.

Fig. 9 is a detail plan section showing the end construction of the slats.

Fig. 10 is a detail perspective view of one of the slats.

Fig. 11 is a detail vertical sectional view showing a line of vision between slats obstructed so that the curtain cannot be seen through.

The particular rolling curtain herein shown for the purpose of illustration, comprises a flexible shutter or curtain 1, comprising a plurality of spaced slats 2 which are strung upon suitable bands or cables 3.

A bottom bar 4 is provided with cable supporting members 5 to which the cables 3 are 55

secured. The supporting members each have a screw 6 arranged in its lower end for the purpose of adjusting the tautness of the cables 5. The head of the screw can be reached by inserting 5. a screw driver through the hole 7, Fig. 5. The upper ends of the cables 3 are locked against the top slat or top bar 8, Fig. 4. A strip of flexible material or fabric 8' is fixed to the top bar 8, and is operatively fastened to a roller 10 element 9 which is provided with a spring 10, Fig. 4, to assist in counter-balancing the weight 10 of the curtain. Inasmuch as the curtain when pushed to an out of the way position makes a sharp turn at the upper edge of the berth; the 15 fabric 8' and the roller 9 may be dispensed with. However, it has been found practicable to include these latter members to assist in the operation of the curtain.

The curtain is adapted to operate in oppositely disposed guides or grooves 11 which are vertically positioned with respect to the berth. The curtain may be used as a partial closure for the berth in connection with a panel for closing the other part of the berth or the curtain 25 may be made the full length of the berth.

The slats 2 are each relatively arrow-shaped, Figs. 5 and 7. Each slat has a pointed end 12, inclined faces 13, and barbs 14. The barbs 14 are connected to the faces 13 by relatively 30 straight sides 15. The barbs 14 are defined by the straight sides 15 and the inwardly inclined faces 16. These barbs provide a groove or recess 17 at the bottom of each slat into which the pointed ends 12 of a lower slat extend a predetermined distance. The slats 2 may be made of any material desirable, but in the present instance, they are shown as being made of metal 18 having a wood core or filler 19. Metal compressed springs 20 are strung on the cables 3, and are arranged between slats to keep the slats a predetermined distance apart. A lower slat has a recess 21 provided in its upper surface, and an upper slat has a recess 22 provided into its lower surface, into which the ends of the compressed springs 20 extend. Washers 20' are positioned in the recesses as clearly shown in Figs. 5 and 6 to prevent the springs 20 from turning or pressing into the filler 19. The filler 19 is preferably made of soft wood and it has been found practical and advantageous to insert these washers on opposite ends of the springs. The washers are strung on the longitudinal vertically extending members 3. These springs are compressed, and are prevented from being extended due to the attachment of the cables to the bottom bar and the top bar. However, they are flexible laterally to permit the curtain to be coiled. By compressing the spring, the curtain is rendered flexible, the slats are properly spaced to permit ventilation between slats, but prevent the slats from being spread apart vertically. Therefore, it is impossible for anyone to pull the slats apart to see between the spaces. The slats are arranged close enough together to prevent anyone from seeing through the slats. In other words, the slats are positioned so that the line of sight is obstructed. The bottom inclined surfaces 16 of each slat may be painted or colored, preferably black, to prevent reflection of light through the spaces between the slats.

The outer ends of each slat 2 has the wood filler portion 19 thereof provided with a slit 23, Fig. 9, to render the ends of the slats somewhat flexible. The slotted ends of the slats permit resiliency and the ends are free to flex, and

these ends may be slightly compressed when they are in the guides or grooves 11 as clearly shown in Fig. 9. The purpose of providing these slits 23 is to provide resilient flexible ends so that the ends may be slightly compressed to fill the guide and thereby prevent the slats from rattling in the guides. However, if the entire sides 15 of each slat were to come in contact with the inner surface of the groove in which the slat slides, considerable friction would be created, and it would make the sliding of the curtain in the grooves relatively hard. Therefore, oppositely disposed protuberances 24 are struck from the metal at the ends of the slat, and only these protuberances engage the inside 15 faces of the grooves or guides. The slit 23 as previously mentioned, tends to permit the slat to be compressed, but it is sufficiently flexible and yieldable so that the slat is free to slide in the groove. The protuberances make it relatively 20 easy to slide the curtain upwardly and downwardly in the grooves.

In Fig. 11 there are shown diagrammatically two slats so spaced that the bottom edges 31 of an upper slat will overlie the pointed end 32 of a lower slat a sufficient distance so that the horizontal lines of vision indicated by the numerals 33 and 34 will be obstructed. Also it will be impossible to look through the curtain at an angle through the space defined by the dotted diagonal lines 35 and 36, because the vision through this space will be obstructed by the inclined faces or surfaces 37.

The curtain when assembled, is flexible to permit the curtain to be readily and easily moved 35 up and down in the guides or grooves 11. The curtain may be used for any purpose desired, such as for partitions for dividing rooms, as shutters for windows, window blinds, or for door openings. One of the principal purposes for the 40 present curtain is for use in Pullman cars. The curtain or curtains, depending upon the number used, is arranged so as to dispense with the conventional fabric curtains now used in making up Pullman berths. These present fabric 45 curtains are unsatisfactory because of drafts, provide no means for preventing pilfering and prevent proper air conditioning in the car. The use of the present rolling curtains, constructed in accordance with this invention, permits air 50 to pass through the curtain, prevents drafts and allows for proper ventilation particularly in co-ordination with the present air conditioning systems now used. Furthermore, the curtain is substantially rigid, as it is supported by grooves 11. 55 In cases where the present curtain is used for Pullman berth purposes, the surfaces 37 may be coated with non-reflecting material 38. This non-reflecting material 38 may be flat black paint or any other suitable material to accomplish the 60 purpose. In actual practice it has been found that light will not reflect when the surfaces 37 of the slats are coated, and it is impossible to see the image or reflection of a person in the berth even though the person is between the curtain and a light. In other words, even at 65 night when the lights on the wall are lit, the image or silhouette of a person in a berth cannot be seen. The invention, therefore, provides a highly desirable dividing medium or partition 70 for Pullman car berths, whereby the berth occupant is assured full privacy, security and proper ventilation. At night the light in the berth will be sufficiently obstructed to prevent it from glaring, shining or reflecting through the curtain. 75

The bottom bar 4 may be provided with a locking member 40. This locking member has a locking bar 41 to which there is attached a draw bolt 42. This draw bolt passes through a 5 roller 43 which is adapted to slide in a groove 11. The locking bar 41 is provided with a slot 44 which is adapted to be engaged by a key to insert or remove the draw bolt 42 from its keeper 45, the keeper comprising a slot extending 10 through the guide. The lower edge of the locking bar 41 is provided with notches 46, 47, which are adapted to be engaged by a spring clip 48. When the spring clip 48 engages the notch 47, the draw bolt will be engaged with its keeper. 15 When the spring clip 48 engages with the notch 46, the draw bolt will be removed from locking position. When the draw bolt is in unlocked position, it will be receded from its keeper, but it will, however, still be engaged with the roller 20 43. Therefore, the draw bolt acts as a bearing for the roller which slides in the groove. On the inner side of the bottom bar, there is a knob or button 49 for manipulating the draw bolt 42. Therefore, on the inside of the curtain the draw 25 bolt can be removed to locked or unlocked position by manipulating the button or knob 49. The draw bolt may be moved to locked or unlocked position from the outside of the curtain by means of a key. A convenient hand hole 50 30 is provided on the inside of the curtain, providing a recess into which the knob or button 49 is set. The movement of the locking plate is limited by the detents 46 and 47 cooperating with the spring 48, and by the length of the slot 51 35 through which the inside locking element extends.

The invention provides a very efficient curtain or blind for various purposes, and the slats may be so positioned or spaced to allow for ventilation, but preventing vision through the slats.

Changes may be made in the form, construction, and arrangement of the parts without departing from the spirit of the invention or sacrificing any of the advantages thereof, and the 45 right is hereby reserved to make all such changes as fairly fall within the scope of the following claims.

My invention is hereby claimed as follows:

1. A curtain movable in guides and comprising a plurality of spaced slats, longitudinal members passing through the slats and upon which the slats are strung, each of said slats having a projecting upper edge and a grooved lower edge, the upper edge of one slat being adapted 55 to extend up into the groove of an upper slat a distance sufficient to permit air to pass through the curtain but obstructing the line of vision so that the curtain cannot be seen through, and flexible incompressible means on the longitudinal members between the slats to hold the slats in spaced relationship.

2. A curtain movable in guides and comprising a plurality of spaced slats, longitudinal members passing through the slats and upon which the slats are strung, each of said slats having a projecting upper edge and a grooved lower edge, the upper edge of one slat being adapted 65 to extend up into the groove of an upper slat a distance sufficient to permit air to pass through the curtain but obstructing the line of vision so that the curtain cannot be seen through, said slats being adapted to resiliently engage the guides at the sides thereof and prevent the curtain from rattling in the guides due to vibration.

75 3. A curtain movable in guides and comprising

ing a plurality of spaced slats, longitudinal members passing through the slats and upon which the slats are strung, each of said slats having a projecting upper edge and a grooved lower edge, the upper edge of one slat being adapted 5 to extend up into the groove of an upper slat a distance sufficient to permit air to pass through the curtain but obstructing the line of vision so that the curtain cannot be seen through, said slats having their ends slotted vertically to flex 10 the ends of the slats and render the ends resilient, the resilient ends engaging the sides of the guides and preventing rattling of the curtain in the guides.

4. A curtain movable in guides and comprising a plurality of spaced slats, longitudinal members passing through the slats and upon which the slats are strung, each of said slats having a projecting upper edge and a grooved lower edge, the upper edge of one slat being adapted to extend up into the groove of an upper slat a distance sufficient to permit air to pass through the curtain but obstructing the line of vision so that the curtain cannot be seen through, said slats having their ends slotted vertically to flex 15 the ends of the slats and render the ends resilient, the resilient ends engaging the sides of the guides and preventing rattling of the curtain in the guides, and outward projections on the said ends, whereby to reduce friction between the guides 20 and slats.

5. A curtain movable in guides and comprising a plurality of spaced slats, longitudinal members passing through the slats and upon which the slats are strung, each of said slats having a 25 projecting upper edge and a grooved lower edge, the upper edge of one slat being adapted to extend up into the groove of an upper slat a distance sufficient to permit air to pass through the curtain but obstructing the line of vision so that the curtain cannot be seen through, and compressed springs on the longitudinal members between the slats to space the slats a 30 predetermined distance, said slats having recesses 35 formed in their upper and lower ends to receive 40 said compressed springs.

6. A rolling curtain comprising a plurality of slats, and supports upon which said slats are strung one above the other, and side guides in which said curtain operates, said slats having 45 their ends slotted vertically whereby the ends of the slats tend to flex and engage the guide on both sides and prevent rattling of the curtain in the guides.

7. A rolling curtain comprising a plurality of 55 superposed slats, said slats having their ends slotted vertically whereby the slats will have springy ends and prevent rattling of the curtain in the curtain guides.

8. A rolling curtain comprising a plurality of 60 superposed metal slats, the metal at the ends of the slats being struck outwardly to provide protuberances which are adapted to engage the guides in which the curtain is guided.

9. A rolling curtain comprising a plurality of 65 superposed metal slats, the metal at the ends of the slats being struck outwardly to provide protuberances which are adapted to engage the guides in which the curtain is guided, fillers inside of the slats about which fillers the metal is 70 fitted.

10. A rolling curtain comprising a plurality of superposed metal slats, the metal at the ends of the slats being struck outwardly to provide protuberances which are adapted to engage the 75

guides in which the curtain is guided, fillers inside of the slats about which fillers the metal is fitted, the ends of said fillers being provided with slits to render the said ends resilient.

5 11. A rolling curtain comprising a plurality of superposed slats, said slats being spaced apart, and flexible incompressible members between said slats to hold the slats in spaced relationship.

12. A rolling curtain comprising a plurality of 10 superposed slats, said slats being spaced apart, and flexible compressed springs arranged between said slats to hold said slats in spaced relationship and preventing said slats from being manually spread to increase the space between 15 slats.

13. A rolling curtain comprising a top bar and a bottom bar, flexible supporting members connecting the top and bottom bars, slats on said members between the top and bottom bars, and 20 means between said slats to space said slats and prevent the slats from being spread apart.

14. A curtain comprising a plurality of spaced slats, longitudinal members passing through the slats and upon which the slats are strung, each 25 of said slats having a projecting upper edge and a grooved lower edge, the upper edge of one slat being adapted to extend up into the groove of an upper slat a distance sufficient to permit air to pass through the curtain but obstructing the 30 line of vision so that the curtain cannot be seen through, said slats being formed of metal formed about fillers, the fillers at each end being formed with a vertical cut to slightly expand the slats at the ends and to make said ends springy whereby 35 they will prevent rattling of the curtain when the curtain is arranged in guides.

15. A curtain comprising a plurality of spaced slats, longitudinal members passing through the slats and upon which the slats are strung, each 40 of said slats having a projecting upper edge and a grooved lower edge, the upper edge of one slat being adapted to extend up into the groove of an upper slat a distance sufficient to permit air to pass through the curtain but obstructing the 45 line of vision so that the curtain cannot be seen through, said slats being formed of metal formed about fillers, the fillers at each end being formed with a vertical cut to slightly compress the slats at the ends and to make said ends springy whereby 50 they will prevent rattling of the curtain when the curtain is arranged in guides, and protuberances on the metal at the ends of said slats to reduce friction between the slats and guides.

16. A curtain comprising a plurality of spaced 55 slats, longitudinal members passing through the slats and upon which the slats are strung, each of said slats having a projecting upper edge and a grooved lower edge, the upper edge of one slat being adapted to extend up into the groove of an upper slat a distance sufficient to permit air to pass through the curtain but obstructing the 60 line of vision so that the curtain cannot be seen through, said slats being formed of metal formed about fillers, the fillers at each end being formed with a vertical cut to slightly expand the slats at the ends and to make said ends springy whereby 65 they will prevent rattling of the curtain when the curtain is arranged in guides, and protuberances

on the metal at the ends of said slats to reduce friction between the slats and guides, and compressed springs between said slats to space the slats and prevent the slats from being spread apart a distance greater than the said springs. 5

17. A curtain movable in guides and comprising a plurality of superposed slats, said slats being strung on a flexible member, said slats being held in invariable spaced relationship by flexible separating means, said flexible separating means 10 being longitudinally incompressible.

18. A curtain movable in guides and comprising a plurality of superposed slats, said slats being strung on a flexible member, said slats being held in invariable spaced relationship by flexible 15 separating means, said flexible separating means being longitudinally incompressible, said slats being so shaped in complementary relationship to each other as to permit the passage of air through the curtain while effectively obstructing line of 20 vision from any angle therethrough.

19. A curtain movable in guides and comprising a plurality of superposed slats, said slats being strung on a flexible member, said slats being held in invariable spaced relationship by flexible 25 separating means, said flexible separating means being longitudinally incompressible whereby said curtain becomes pilfer-proof, it being impossible to pry said slats apart or increase the width of the space between them, said slats being so 30 shaped in complementary relationship to each other as to permit the passage of air through the curtain while effectively obstructing line of vision from any angle therethrough.

20. A flexible ventilating curtain movable in 35 guides comprising a plurality of superposed spaced slats flexibly mounted upon flexible cables running through said slats, said slats being held in invariable spaced relationship, said slats being shaped in complementary relationship with 40 each other so as to allow the passage of air while obstructing line of vision from any angle through the curtain, said slats also being slotted at the ends to provide resilient engagement with the sides of the guides preventing rattling of the 45 curtain in the guides.

21. A rolling curtain for use in railway berths comprising a spring urged rotatably mounted shaft, flexible vertical members, a top bar, a bottom bar connected to said members, a plurality of slats mounted on the flexible members between said top bar and bottom bar, said slats having their lower edges provided each with a recess and their upper edges provided each with a projection, the projection on the upper edge of 55 a lower adjacent slat extending into the recess on the bottom of an upper adjacent slat a predetermined distance so as to prevent vision between the slats but to permit air to pass through, spacing means between adjacent slats to hold 60 the slats a predetermined distance apart in proper spaced relationship, means for tightening or loosening the flexible members to increase or decrease the spaces between slats and flexible means operatively connecting said top bar to 65 said spring-urged shaft whereby the curtain may be shifted bodily to and from the shaft.

EDWARD B. NOTTINGHAM.
